UNITED STATES PATENT OFFICE.

WALTER CLARKE BELLows, OF CHICAGO, ILLINOIS, ASSIGNOR, BY MESNE ASSIGNMENTS, TO PELOUZE MANUFACTURING COMPANY, OF CHICAGO, ILLINOIS, A CORPORATION OF ILLINOIS.

MICROPHONIC ATTACHMENT FOR TELEPHONE-TRANSMITTERS.

1,248,998.

Specification of Letters Patent.

Patented Dec. 4, 1917.

Application filed July 12, 1916. Serial No. 108,920.

To all whom it may concern:

Be it known that I, WALTER CLARKE BELLows, a citizen of the United States, residing at Chicago, in the county of Cook and State 5 of Illinois, have invented a new and useful Improvement in Microphonic Attachments for Telephone-Transmitters, of which the following is a specification.

My invention relates to improvements in 10 the class of devices used as attachments for the mouthpieces of telephone-transmitters to so augment the sounds uttered into a transmitter, that they may be in a tone so subdued as to be unintelligible to others 15 who may be in the room with, or near the user of the telephone, but clearly audible to a listener at the receiving end.

One object of my invention is to provide 20 an improved construction of attachment in the class referred to, with the advantage, among other advantages, of greatly augmenting the microphonic effect, so that even whispered speech will be rendered clearly audible at the receiving end of the telephone; and a further object is to so insulate 25 an attachment in the present class as to prevent its enveloping wall from being vibrated by the sounds transmitted through the attachment in speaking, thus to enhance 30 the privacy of telephonic conversation.

In the accompanying drawings, Figure 1 is a view showing my improved attachment in longitudinal sectional elevation and in size considerably enlarged over that in 35 which the device is constructed for use; Fig. 2 is an end view of the same, presenting the end to be attached to a telephone mouthpiece; Fig. 3 is a section on line 3, Fig. 1; Fig. 4 is an end view presenting the receiving end of the attachment; Fig. 5 is a broken view in longitudinal sectional elevation of the inner vibratory cylinder and parts contained therein, showing a modification of the diaphragms, and Fig. 6 is a face view 45 of one of the two diaphragms of Fig. 5.

A hollow cylinder 7, of sheet-metal, terminates at one end in an outwardly tapering member-forming section 8, in the form of a cone-frustum. These members are of 50 very thin sheet-metal, preferably steel, to render them highly sensitive to vibration under the influence of sound passing through the device. Concentrically within the section 8, and spaced therefrom, is a

similar tapering member 9, of very thin 55 sheet-metal.

A spiral spring 10, of very fine spring-wire, and formed preferably of two connected coils, as shown, is supported centrally in the cylinder 7 by an equally fine wire 60 11, fastened at one end to the inner cylinder-wall and at its opposite end to the spring 10 between its coils. On the outer end of one coil is fastened, at its center, as by soldering, to cover the inner end of the 65 member 9, in spaced relation thereto, a diaphragm-forming disk 12 of very thin sheet-metal, preferably steel; and a similar diaphragm 13 is fastened in the same manner on the outer end of the other coil. A rigid 70 hollow cylinder 14, of relatively thick metal, preferably aluminum, though it may be formed of any suitable material, surrounds concentrically the cylinder 7 and is separated therefrom by a dead-air space 15. This 75 space is closed at one end by a flanged ring 16 spacing apart the two cylinders and having secured to it the marginal flange 17^a of the rounded neck-portion of an outwardly flaring tubular extension 17 of the cylinder 80 7, this extension being preferably corrugated circumferentially, as represented, to increase its surface and augment its sound-transmitting action. An annular washer 18, preferably of rubber, is secured in the outer 85 face of the flange 17^a to bear against the edge of a telephone mouthpiece, indicated at 19, when the attachment is used as herein-after described. A wire-mesh screen 20 is shown to be provided at the inner end of the 90 extension 17, to afford a shield against mischievous or accidental insertions into the attachment; and a lip 21 extends in semi-circular form from about the outer end of the cylinder 14 to hook over the outer edge 95 of the flaring mouthpiece 19 in applying the attachment to its operative position thereon.

The receiving end of my improved attachment terminates in a tapering neck-portion 22 extending from about the cylinder 14 and carrying and securing in their spaced relation the tapering members 8 and 9 through the medium of pins 23 and 24 extending at right-angles to each other through the tapering end-portions of these members, and 100 through the adjacent portion of the neck 22. A cup-like flange 25 surrounds this neck near its outer end and forms with the lat-

ter an annular socket for confining a mouthpiece 26 at its flange 27, this mouthpiece being preferably removable and hollow or "pneumatic" and formed of soft rubber.

5 To use my attachment it is applied to a receiver 19 by hooking over the latter the lip 21, which brings the attachment into close contact, at the washer 18, with the edge of the receiver. This introduces the 10 flaring extension 17 centrally into the telephone-receiver and into desirably close proximity to the diaphragm thereof, while rigidly supporting the attachment in alignment with the receiver mouthpiece 19.

15 The user, with lips inserted into the mouthpiece 26, directs speech or other form of sound into the telephone through the attachment. The parts 9, 8 and 7 and the spring-connected and supported diaphragms 20 12 and 13, are so delicately vibratory and in such relation to each other that the sounds vibrate them and the extensions 17, and becomes progressively augmented to a degree that when even it is merely whispered it so amply vibrates the diaphragm in the telephone-receiver as to be distinctly audible at the receiving end of the telephone.

Without the dead-air space 15 enveloping the vibratory elements of the attachment, 30 even speech in a subdued tone or whisper might be audible to one in a position to overhear the telephone-conversation, when it is desired to keep it secret. The dead-air space, however, prevents transmission of the 35 vibrations to the enveloping cylinder 14, and thus renders the speech inaudible, or at least unintelligibly audible to persons in the same room with, or in close proximity to the user of the attachment.

40 The sound-augmenting effect is materially enhanced by providing the diaphragms 12 and 13 in the form, illustrated in Figs. 5 and 6, of bladed or vaned wheels 12^a and 13^a, like those used in electric fans, and 45 journaling them on the outer ends of the spring-coils 10, then forming journals. These wheel-like diaphragms, which are vibrated, like the corresponding diaphragms 12 and 13, by the sound-waves of speech, 50 are also rotated thereby on the journals; and in revolving they tend to direct the sound more or less forcibly from the wheel 12 against the cylinder 7, and from the latter through the wheel 13^a, which directs them in a similar way through the flaring 55 tubular extension 17.

While I have herein mentioned my attachment only as applicable to telephone transmitters, it is also intended for use on dictaphones and speaking-tubes.

60 I realize that considerable variation is possible in the details of construction thus specifically shown and described, and I do not intend by illustrating a single specific or 65 preferred embodiment of my invention to

be limited thereto, my intention being in the following claims to claim protection upon all the novelty there may be in my invention as fully as the state of the art will permit.

What I claim as new and desire to secure 70 by Letters Patent is:—

1. An attachment of the character described, comprising a forwardly flaring member of very thin material open at its ends, and provided at its smaller end with 75 a mouthpiece, a diaphragm of similarly thin material vibratory supported to extend adjacent to the flaring end of said member, and a sound-insulating chamber enveloping said member and diaphragm.

2. An attachment of the character described, comprising a forwardly flaring member of very thin material open at its ends and provided at its smaller end with a mouthpiece, a diaphragm and a spring, 85 both of similarly thin material, the spring supporting the diaphragm near its center to extend adjacent to the flaring end of said member and vibrate freely throughout, and a sound-insulating chamber enveloping said 90 member and diaphragm.

3. An attachment of the character described, comprising an inner thin hollow cylinder terminating at its rear end in an outwardly tapering member, sound-vibrated 95 members of thin sheet-metal supported within said cylinder, an outer cylinder of relatively thick material surrounding and forming about the inner cylinder a sound-insulating air-space, a mouthpiece on the 100 rear end of said outer cylinder and an outwardly flaring tubular extension on the forward end thereof.

4. In an attachment of the character described, the combination of an inner hollow 105 cylinder, sound-vibrated members of thin sheet-metal within said cylinder, and an outwardly flaring circumferentially corrugated tubular extension at the front end of said cylinder.

5. In an attachment of the character described, the combination of a thin hollow cylinder terminating at its rear end in an outwardly tapering member, a similar member supported within and in spaced relation 115 to said first-named member, a tubular extension at the forward end of said cylinder, and a spring-carried diaphragm interposed in said cylinder between and in alignment with said inner tapering member and flaring 120 extension.

6. In an attachment of the character described, the combination of a hollow cylinder of thin sheet-metal, and a bladed-wheel-like diaphragm spring-supported rotatably 125 in said cylinder to be interposed centrally in the passage therethrough.

7. In an attachment of the character described, the combination of a hollow cylinder of thin sheet-metal terminating at its 130

5 rear end in an outwardly tapering member, a similar member supported within and in spaced relation to said first-named member, a spring-carried spring extending lengthwise in said cylinder, a diaphragm on the outer end of the lengthwise-extending spring in alinement with and spaced from the flaring end of said inner member, and a diaphragm on the opposite end of the last-named spring and alining with said first-named diaphragm.

10 8. In an attachment of the character described, the combination of a hollow cylinder of thin sheet-metal terminating at its rear end in an outwardly tapering member, a similar member supported within and in spaced relation to said first-named member, a spring-carried spring extending lengthwise in said cylinder, a bladed wheel-like diaphragm journaled on one end of the 15 lengthwise-extending spring in alinement with and spaced from the flaring end of said inner member, and a diaphragm on the opposite end of the last-named spring and 20 alining with said first-named diaphragm.

25 9. In an attachment of the character described, the combination of a hollow cylinder of thin sheet-metal terminating at its rear end in an outwardly tapering member, a similar member supported within and in spaced relation to said first-named member, a spring extending into said cylinder from its wall, a spiral spring formed of end-coils 30 alinedly connected together and connected

between the coils with the inner end of said first-named spring to be vibratorily supported thereby and extend lengthwise in said cylinder, a diaphragm on the outer end of one of the rear coils in spaced relation to the flaring end of said inner member, and a diaphragm on the opposite end of the forward coil.

35 10. An attachment of the character described, comprising an inner hollow cylinder of thin sheet-metal terminating at its rear end in an outwardly tapering member, a similar member supported within and in spaced relation to said first-named member, a spring-carried spring extending lengthwise in said cylinder, a diaphragm on the outer end of the lengthwise-extending spring in alinement with and spaced from the flaring end of said inner member, a diaphragm on the opposite end of the last-named spring and alining with said first-named diaphragm, an outer cylinder enveloping said inner cylinder and forming about the latter a sound-insulating air-space, a mouthpiece on the rear end of the outer cylinder and a tubular extension on the forward end thereof, and means in the outer cylinder for separably connecting it with a telephone-transmitter mouthpiece.

WALTER CLARKE BELLOWS.
